UNITED STATES PATENT OFFICE.

JOHN LOUIS LUTJEN, OF NEW YORK, N. Y.

DOOR AND TREADLE OPERATING MEANS FOR SELF-PLAYING PIANOS.

No. 861,743.

Specification of Letters Patent.

Patented July 30, 1907.

Application filed March 8, 1907. Serial No. 361,221.

To all whom it may concern:

Be it known that I, JOHN LOUIS LUTJEN, a citizen of the United States, residing at New York city, Brooklyn, county of Kings, State of New York, have invented new and useful Improvements in Door and Treadle Operating Means for Self-Playing Pianos, of which the following is a specification.

This invention relates to improved means for manipulating the doors that inclose the treadles and the music rollers of a self-playing piano, and also to improved means for swinging the treadles into or out of their operative position. The construction is such that the doors and treadles may be operated in convenient manner by means of hand levers pivoted to the bottom of the key-board and within easy reach of the operator.

In the accompanying drawings: Figure 1 is a front elevation of a self-playing piano embodying my invention; Fig. 2 a rear view of the door and treadle actuating mechanism, showing the piano case in section; Fig. 3 a view similar to Fig. 2, showing the parts in different position; Fig. 4 a vertical transverse section of the treadle operating mechanism on line 4—4, Fig. 6; Fig. 5 a similar section through the treadle-box of Fig. 4, and showing the parts in different position; Fig. 6 a section on line 6—6, Fig. 4, showing the treadles raised, and Fig. 7 a bottom view of the key-board.

The piano case 10 is provided with an upper sliding door 11 that controls access to the chamber containing the music roller. It also has two lower doors 12, 13 controlling access to a box 14 which is adapted to receive the treadles 15 when the latter are swung inwards. These treadles are pivoted to arms 16 that are in turn pivoted at 17 to bearings 18 arranged in the forward part of box 14.

In order to simultaneously operate all three doors 11, 12, 13, there is pivoted at 19 to the lower side of key-board 20, a hand lever 21. This lever may be oscillated by a knob 22 and is guided by a keeper 23. The rear forked end of lever 21 straddles a pin 24 of a horizontally movable bar 25. This bar, by bell crank 26, rod 27, bell crank 28, link 29, lever 30 and link 31, swings a lever 32 having an upper slot 33 that engages a pin 34 on the back of door 11. By the means described, a turn of lever 21 will cause a sliding movement of bar 25, which, in turn, will either open or close door 11, as will be readily understood.

Doors 12, 13 are operated by reciprocating bar 25 in the following manner: To bar 25 is pivoted near one end, a lever 35 connected by link 36, lever 37 and link 38, to a lever 39. This lever is fulcrumed at 40 and has a slot 41 that embraces a pin 42 on back of door 12. At its other end there is pivoted to bar 25, a lever 43, connected by a link 44 to a lever 45 fulcrumed at 46 and having a slot 47 that embraces a pin 48 on back of door 13. Thus by moving bar 25 in one direction, doors 12, 13, as well as door 11, will be opened, while by mov-

ing the bar in the other direction, all three doors will be closed.

The means for manipulating the treadles are as follows: To the lower side of key-board 20 is pivoted at 49, 60 a second hand lever 50 having knob 51 and guided by a keeper 52. The rear forked end of lever 50 straddles a pin 53 of a second horizontally slideable bar 54. This bar has a pair of pins 55 engaging the slotted upper ends of bell cranks 56 which are connected by rods 57 and 65 bell cranks 58, to levers 59 fulcrumed at 60 within the back of box 14. The lower ends of levers 59, are, by links 61, connected to the arms 16 of treadles 15. By the means described, a movement of lever 50 in one direction will cause the treadles to be swung upwards into 70 box 14, (Fig. 5), while a movement of the lever in the opposite direction will cause the treadles to be lowered into their operative position, (Fig. 4).

Means are provided for so interlocking the door operating mechanism with the treadle operating mechanism, 75 that the latter cannot be moved when the doors are closed, and that the former cannot be moved when the treadles are lowered. In this way injury to the mechanism, owing to untimely efforts to operate the same, is prevented.

To lever 37 is pivoted at 62 a slotted stop 63 guided by means of a pin 64. When the position of the parts is such that the doors are closed, stop 63 projects with its free end over one of the bell cranks 56 that transmit movement to the treadles. In this way the latter will 85 be locked against lowering as long as the doors remain closed, (Fig. 2). In opening the doors, stop 63 is withdrawn from bell crank 56, (Fig. 3), so that the treadles are now free to be lowered.

To the second bell crank 56 is pivoted at 65 a slotted 90 stop 66 guided by a pin 67. The free end of this stop is arranged opposite the upper arm of lever 43. When the treadles are swung down, stop 66 will engage lever 43, (Fig. 3), and thus prevent the doors from being closed. By swinging the treadles up, stop 66 will be 95 withdrawn from lever 43, and thus permit the doors to be closed.

I claim:

1. A device of the character described, comprising a piano case, a chamber, a music roller journaled therein, a treadle box, separate doors adapted to close said chamber and box, and means for simultaneously operating said doors, substantially as specified.

2. A device of the character described, comprising a piano case, a chamber, a music roller journaled therein, a treadle box, separate doors adapted to close said chamber and box, a handle, and means connected to the handle for simultaneously operating said doors, substantially as specified.

3. A device of the character described, comprising a piano case having a key-board, a handle carried thereby, a chamber, a door controlling said chamber, a treadle box, a pair of doors controlling said box, and means connected to the handle for opening and closing said three doors, substantially as specified.

- 2
4. A device of the character described, comprising a piano case having a key-board, a handle carried thereby, a slideable bar connected to the handle, a chamber, a door controlling said chamber, a treadle box, a pair of doors controlling said box, and means connected to the bar for opening and closing said three doors, substantially as specified.
5. A device of the character described, comprising a treadle-box, doors controlling the same, treadles adapted to be folded into the box, means for operating the doors, means for operating the treadles, and means for interlocking the door operating means with the treadle operating means, substantially as specified.
10. A device of the character described, comprising a treadle-box, doors controlling the same, treadles adapted to be folded into the box, means for operating the doors, means for operating the treadles, and means for interlocking the treadle operating means with the door operating means, substantially as specified.
15. A device of the character described, comprising a treadle-box, doors controlling the same, treadles adapted to be folded into the box, means for operating the doors, means for operating the treadles, and means for interlocking the treadle operating means with the door operating means, substantially as specified.

7. A device of the character described, comprising a piano case having a key-board, a first handle carried thereby, a slideable bar engaged by the handle, a treadle-box, a pair of doors controlling the same, a first and a second lever operatively connecting the bar to said doors, a second handle carried by the key-board, a second slideable bar 25 engaged thereby, a pair of treadles, a first and second bell crank that operatively connect the second slideable bar to the treadles, a stop on the first lever adapted to engage the first bell crank, and a stop on the second bell crank adapted to engage the second lever, substantially as 30 specified.

Signed by me at New York city, Manhattan, N. Y., this seventh day of March, 1907.

JOHN LOUIS LUTJEN.
